UNITED STATES PATENT OFFICE.

FERNANDO CASABLANCAS PLANELL, OF SABADELL, SPAIN.

SCOURING MACHINE FOR WASHING FABRICS OF WOOL AND ITS MIXTURES.

Original application filed April 16, 1926, Serial No. 102,508, and in Spain April 21, 1925. Divided and this application filed October 29, 1927. Serial No. 229,737.

My invention relates to machines for washing fabrics of wool and its mixtures, known as scourers, and the subject-matter thereof constitutes a division of my co-pending application Serial No. 102,508. The object of the invention is to ensure uniform distribution of the pressures exercised by the washing cylinders or rollers on the pieces to be washed, in the case of more than two pieces in the direction of width of the machine are being simultaneously washed.

A further object of this invention is to improve the washing machine disclosed in my above referred to co-pending application, by so positioning the bearings for the upper rollers that easy access may be had to them for the purposes of inspection, replacement, lubrication, etc.

The usual scouring machines comprise two cylinders or rollers, the lower one of which is mounted on bearings of fixed position, whilst the upper roller rests on the lower one and is mounted in swivel bearings which allow it to take up a certain inclination in its vertical plane. Between these two rollers are caused to pass twisted to the shape of a rope or "ribbon" the pieces of fabric to be washed. As long as only a single piece, or two pieces, one at the side of the other, are caused to pass through the machine, the top roller always presses properly on the pieces of fabric to be washed, and in the case of two pieces passing, the pressure of the top roller is evenly distributed between the two, even if one of the two pieces should be of a greater thickness than the other or only thicker along a portion of its length. On the contrary, when it is desired to pass through the machine three or four pieces, side by side, the top cylinder or roller properly presses only on two of these pieces, whilst it presses on the remaining one or two in a faulty manner, so that the pressure of the roller is no longer evenly distributed over all the pieces, with the result that the washing is faulty.

This invention consists substantially in dividing the top roller into two parts arranged in line with each other and each mounted in such a manner as to enable it to assume in its vertical plane the inclination required in order to exercise a proper pressure on the pieces. In this way, it is possible to pass under each of the two top rollers two

pieces of fabric, and the roller will exercise 55 a uniform pressure on both, in such a manner that four pieces can be washed in the machine with the same perfection as if only two were being washed.

A construction of a scouring machine with 60 the improvements forming the subject of this invention, is shown in the accompanying drawings.

Figure 1 shows diagrammatically the arrangement of an ordinary machine for washing simultaneously two pieces.

Figure 2 shows, also diagrammatically, the arrangement of an ordinary machine for washing simultaneously four pieces.

Figure 3 shows, also diagrammatically, the 70 arrangement of a machine for washing four pieces at the same time, built in accordance with this invention.

Figure 4 is a side elevation of a machine built in accordance with this invention.

Figure 5 is a horizontal section of the same machine on line V—V of Figure 4.

Figure 6 is a vertical section of the same machine on line VI—VI of Figure 4.

The normal or standard washing machine 80 for two pieces in the direction of its width, comprises; see Figure 1, chiefly two rollers, the bottom one 1 and the top roller 2. The former has the journals working in two bearings secured to the bed of the machine, and 85 the second one, 2, has them working in two special journals, the construction of which allows the roller to oscillate, its axis remaining in the vertical plane passing through the same. This figure shows, without requiring 90 any further explanation, how even in the case of two pieces 41 and 42 of unequal thickness, the pressure due to the weight of the roller 2, added to that which eventually could be exercised on its bearings, is distributed 95 among the two pieces which come between the roller 2 and the roller 1, but the pressure on the pieces never ceases at any moment as long as the rollers are not excessively worn out.

The standard machines for washing three or four pieces in the direction of width, see Figure 2, do not show any material difference from the preceding one, except as regards the width of the rollers 1 and 2. It is shown in this figure that of the four pieces which are being washed: 41, 42, 43 and 44, in all the places where their thickness is not the

same, two of them, for instance 41 and 43, have no pressure acting on them, and only 42 and 44 are exposed to pressure, the result of which is a faulty washing.

5 Figure 3 shows the scouring machine for four pieces with the improvements according to this invention. The bottom roller 1 is supported, like in a standard machine, in two bearings secured to the bed of the machine, whilst the top roller is divided in the centre and forms two rollers 2, 2 entirely independent of each other. Each of these rollers 2 rests on the corresponding portion of the bottom roller 1, with interposition of 10 the pieces of fabric to be washed, and to that end these rollers are mounted in such a manner that their spindle can oscillate or swing in the vertical plane so as to ensure that they shall always rest or press on the pieces of 15 fabric. In this way is obtained a reliable distribution of the pressure on the pieces to be washed, similarly to the case of Figure 1, but with the advantage that four pieces can be washed at the same time in an absolutely 20 perfect manner.

The method of mounting these top rollers 2 so as to ensure their properly pressing on the pieces of fabric to be washed, may vary according to individual cases; one preferred 30 arrangement according to this invention consists in mounting the spindle of each of the two rollers 2 on brackets or supports arranged at one and the same side of the machine so as to enable the roller to execute the 35 necessary movements.

Figures 4 to 6 show this method of construction. In the same, the bottom roller 1 is supported in bearings 3 secured to the frame of the machine in the usual manner, 40 and generally speaking, the whole construction of the machine is the usual one, with the exception of the top rollers 2 and of the mechanism for guiding these rollers. This guide mechanism is constituted by a fixed 45 horizontal bar 5 arranged approximately level with the spindle 10 of the top roller 2 and in front of the said roller. This bar is secured to the bed by means of brackets 4, 4 and projects outwards at both sides of the 50 bed. To the said projecting portions 5 are pivoted two arms 6, 6 which extend horizontally rearwards. These arms are also hollow in this portion, and in their interior are 55 pivoted pins 7, 7 which are made in one piece with the lower part of the bearings 71, 72.

These bearings, although shown in the drawings provided with continuous lubrication by means of depending rings 14, could be with sight feed or any other system of 60 lubrication. They could also be rolling instead of sliding by means of balls, rollers and the like. In the drawing, they are shown sliding and with separately attached blocks or shoes, but they could also be cast in one 65 with the bearing. Also being separate they

could have spherical seats in place of cylindrical ones, which would ensure better adjustment of the bearings to the oscillations of the journal.

One of these two bearings, 71, must be with 70 fixed journal so as to prevent the spindle 10 of the roller 2 from sliding in the direction of its length, for which reason this spindle 10 is provided with flanges, 19, 19 engaging with the front portions of the bearing 71. 75

It remains to be mentioned that for locking or stopping the swivelling movements of the arms 6, 6 relatively to the pins or rods 7, 7, are provided rings 9, 9 secured by means of set screws or pins to the rods 7, 7. For 80 the same purpose are used the collars 8, 8 in order that with the swivel movement of the arms 6, 6 relatively to the bar 5 secured to the bed.

It will be clear from the preceding description that the spindle 10 which is that of the top roller 2, is completely free to move in its vertical plane so that it can adjust itself to the differences in thickness of the pieces held between the rollers 2 and 1. These rollers 90 which are usually made of strong wood such as oak, mahogany, etc., are secured to their spindles which are driven in tight and are square or round and by means of safety keys or wedges combined with soft iron rings and 95 introduced hot into recesses provided for the purpose in the front faces of the rollers. In Figures 5 and 6 this arrangement is not shown, but it does not differ substantially from that described, with the exception that 100 the spindle 10 is secured to the roller 2 by means of a sleeve 11 of cast iron, the object of which is to add to the weight of the roller 2 so as to ensure a stronger pressure.

With the same object, the arms 6 corresponding to the outside bearings, are extended to the front of the machine, forming an arm 17 which can be provided with a balance weight 18 the position of which can be adjusted on the arm 17, and the inner arms 6 are extended rearwards by an arm 15 which projects from the base of the bearing, is rigidly secured to it and can receive a sliding weight 16. These two weights 16 and 18, on their size and position being duly combined, balance the weight of the outer bearings and also increase the pressure of the roller 2 on the roller 1. 105 110 115 120

In spite of the guide mechanism being free from any important stresses owing to its being able to follow the movements of the rollers 2, but for the purpose of reducing these stresses to a minimum, the upper rollers 2 are arranged somewhat in front of the roller 1 (in a manner known per se) in order that the 125 tendency of the former to slide on the latter towards the front portion of the machine, should balance the strain which the bottom roller 1 produces on the top rollers 2 when the machine is working in order to overcome 130

the torque of the rollers 2 which play the part of driven rollers. This arrangement can be seen in Figure 4.

The machine disclosed in my parent application, above referred to, has the advantage of occupying relatively small space, but on the other hand the bearings remain enclosed within the cylinders and are difficult of access; and the lubrication of the bearings is also difficult. According to the present invention the arrangement of the bearings has the advantage that the two bearings upon which rest the axle of each upper cylinder are readily accessible, and may also be quite easily lubricated. The present arrangement also facilitates inspection and care of these bearings and in certain cases it is more satisfactory than the arrangement of the machine disclosed in the parent application.

Moreover to these machines with the improvement forming the subject of this invention are applicable any others that are generally applied to machines with an undivided top roller, such as knocking off motion for preventing the pieces from being damaged when they get entangled with each other, protective covers, and the like.

I claim:—

1. In a scouring machine for washing fabrics of wool and its mixtures, a lower roller which revolves upon bearings fixed to the frame of the machine, two upper rollers running loose the one in prolongation of the other and which rest upon the lower roller, an axle fixed to each one of these upper rollers and which is extended towards the outside of the machine and two bearings in which rests and revolves the extension of the said axle, these bearings being mounted upon the

frame of the machine in such a way that the axle of the roller may move freely in its vertical plane so that the roller shall adapt itself conveniently to the pieces of fabric which are being washed.

2. In a scouring machine for washing woolen fabric, a roller, bearings for said roller supported by the frame of the machine, a pair of rollers superimposed upon the first roller and adapted in conjunction with the first roller to have pieces of fabric pass therebetween, an axle for each of the pair of rollers, said axles having prolongations extending beyond the frame of the machine, a pair of bearings mounted on each side of the frame of the machine for the axles of the pair of rollers, each pair of bearings being yieldably mounted upon the frame beyond the sides thereof to admit the movement of the axles and rollers toward and from the lower roller and to admit of easy access to the bearings.

3. In a scouring machine for washing fabrics, a roller mounted on the frame of the machine, a pair of rollers superimposed upon the first roller, an axle for each of the last mentioned rollers, said axles having prolongations extending outwardly of the sides of the frame of the machine, a pair of bearings mounted on each side of the frame for receiving the prolongations of the axles and supporting the latter, said bearings being yieldably mounted on the frame to admit yielding of the axles and rollers thereon to accommodate material of various thicknesses between said first roller and said pair of rollers.

In testimony whereof I have signed my name to this specification.

FERNANDO CASABLANCAS PLANELL.
